UNITED STATES PATENT OFFICE.

JOHN R. STARK AND MEADE S. HARWELL, OF NASHVILLE, TENNESSEE.

ELECTRIC SIGN.

1,227,686.

Specification of Letters Patent. Patented May 29, 1917.

Application filed April 25, 1916. Serial No. 83,470.

To all whom it may concern:

Be it known that we, JOHN R. STARK and MEADE S. HARWELL, citizens of the United States, residing at Nashville, in the county 5 of Davidson and State of Tennessee, have invented certain new and useful Improvements in Electric Signs, of which the following is a specification.

Our invention relates to new and useful 10 improvements in signs and more particularly to electrically lighted signs in which light bulbs included in a number of independent circuits are provided and in which a circuit breaker is arranged to intermittently 15 open and close the various circuits so that a portion of the lights flash on at one time, are later extinguished and replaced by other lights, the lights being of different colors when desired.

20 One of the primary objects of our invention consists in the provision of a sign of the above character possessing the added attraction of a movable figure which is also preferably illuminated by certain lights.

25 In this connection and in this particular instance, we have provided a sign including a female figure supported upon a swing which is driven by suitable gearing forming a portion of our invention and have provided 30 a number of lights of different colors within the figure in order that the figure which is formed of transparent or translucent material may be lighted up in such a way that the costume worn will appear at 35 one time to be of one color and at another time of another color.

A still further object of the invention 40 consists in the provision of a novel form of mechanical movement for actuating the figure supporting swing.

Other and incidental objects will appear as the description proceeds and in the drawings wherein we have illustrated the preferred embodiment of the invention and 45 wherein similar reference characters designate corresponding parts throughout the several views,

Figure 1 is a front elevation of a sign 50 constructed in accordance with our invention a portion of the frame of the sign being broken away to more clearly illustrate certain details,

Fig. 2 is a fragmentary perspective view 55 illustrating the means for actuating the figure supporting swing,

Fig. 3 is a diagrammatic view showing

one wiring method which may be employed in illuminating our sign.

Our invention, in its preferred form, includes a supporting frame 10 which carries 60 the swing 11 supporting the illuminated figure 12 and which also supports the sign proper 13 which in the present instance, is constructed in the form of an arch. The supporting frame 10 is in the form of an inverted 65 U the sides 14 and top 15 of which may be constructed of wood, sheet metal, or other suitable material painted upon the outside with any desired color or colors or otherwise suitably ornamented. This frame 70 is of hollow construction and its front walls are provided with electric light receiving sockets in which are mounted an outer series of electric light bulbs 16 and an inner series of electric light bulbs 17, the bulbs of 75 one series being of a different color from those of the other and the two series extending completely around the frame. The arch shaped sign proper 13 is also of hollow construction and is provided with a semi-circular 80 series of openings to receive light bulbs 18 of any desired color and with a plurality of openings through which project sockets receiving light bulbs 19 so arranged as to form the letters of the sign, these light bulbs 85 also being preferably of a distinguishing color. Obviously, light bulbs of any color or any number of colors may be employed and each series of bulbs may be of the same color or may consist of an assortment of two or more colors dependent upon the effect desired. The lower wall 20 of the inverted U-shaped frame 10 is formed adjacent each of its ends with rearwardly extending slots 21 through which project rods 22 connected at 90 their lower ends to the seat 23 of the swing and the figure 12 is seated upon this swing and secured against accidental displacement therefrom in any suitable manner. The rods 22 are swingingly supported within the top 95 of the frame in a manner which will be later explained. This figure in whole or in part is constructed of glass or other suitable transparent or translucent material such as celluloid in order that its costume may be 100 illuminated and colored from light bulbs inclosed within the figure. Any number of light bulbs of any desired color or colors may be inclosed within the figure and connected either in independent circuits or in 105 certain of the circuits including the bulbs 16, 17, 18, and 19. In the present figure, we

100

105

110

115

have illustrated light bulbs 24, 25, and 26 of different colors each in a circuit independent of the others, the wires for these circuits being passed from the figure through the rod 5 supporting the swing and so into the hollow frame.

Secured within the top member of the frame 10 and arranged in pairs therein, are L-shaped brackets 27 arranged to provide 10 parallel spaced arms to receive eyes 28 formed upon the upper ends of the swing rods 22, the rods being swingingly connected to the brackets by means of pins 29. As a means for oscillating the swing, we provide 15 an electric motor 30 or other suitable source of power which is preferably mounted at any convenient point within the frame and about the shaft of which is trained a belt or chain 31 which is also trained about a pulley 20 or sprocket wheel 32 fixed upon a shaft 33 extending longitudinally of the upper member 15 of the frame 10 and journaled in suitable bearings 34 located within the frame. The free end of this shaft carries a disk 35 25 having an eccentric pin 36 and a crank arm 37 is swingingly connected at one end to the pin 36 and at its other end to a laterally directed arm 38 extending from the adjacent swing rod 22, the arm 38 being movable in 30 the slot 39 of a guide plate 40 mounted within the frame member 15. From the foregoing description, it will be apparent that when the motor 30 is driven, the shaft 33 will be revolved and will act through the 35 crank arm 37 to impart an oscillatory movement to the swing rods 22 and so to the swing as a whole.

Any suitable or desired arrangement of circuits for the various series of lights previously described as well as any preferred form of controlling mechanism for opening and closing the circuits may be provided and we do not wish to be limited to any specific arrangement. However, in order to insure a clear understanding of our invention we have illustrated one system diagrammatically in Fig. 3. In this figure, we show a metallic drum 41 rotatable with a shaft 42 driven by a belt 43 passed about a 50 pulley 44 upon the shaft. The belt may be trained about a pulley mounted upon the shaft of the motor 30 or may receive power from any suitable source. The peripheral face of the drum 41 is provided with a 55 covering 45 of insulating material such as fiber or vulcanized rubber and this covering at suitable intervals is cut away to receive contact strips 46, 47, and 48 which extend peripherally of the drum. In the 60 present instance, these strips are shown as each extending through substantially one-third of the circumference of the drum and in staggered relation thereabout so that cooperating contact brushes 49, 50 and 51 arranged parallel to each other and engaging

the periphery of the drum will be successively engaged by their respective contact strips. A suitable lighting current is supplied to the drum by a conductor 52 leading from any suitable source of electrical energy 70 such as a dynamo 53 to a brush 54 engaging one end of the drum, and circuits are intermittently completed through the drum and contact strips and back to the dynamo by way of the conductors 55, 56, and 57. In 75 the present instance, we have assumed that all of the bulbs constituting the outer series 16 about the frame of the sign are included in the wire 55 and also that the bulb 24 within the figure is included in this wire. 80 In like manner, we have assumed that all of the bulbs 17 constituting the inner series of lights about the frame are included in the wire 56 as well as the bulb 25 within the figure. In like manner, all of the bulbs 18 85 and 19 constituting the sign proper are included in the wire 57 together with the remaining bulb 26 of the figure. In the diagram, however, we have only shown two or three of the bulbs of each series as connected in a circuit for the sake of simplicity.

In operation, assuming that the motor 30 is driven and that power is imparted either from this motor or from another suitable 95 source to the shaft 42, it will be clear that the various lighting circuits above described will be intermittently closed and opened and the swing will be continuously oscillated.

As many different figures may be mounted upon the swing or upon a swingingly supported support in the sign and as an infinite number of lighting arrangements may be employed in connection with the 105 sign, we do not limit ourselves to such specific details but reserve the right to make any changes within the scope of the appended claims.

Having thus described our invention, 110 what we claim and desire to secure by Letters Patent is:

1. In a sign, a sign frame of hollow construction, a shaft mounted for rotation within the frame, means for driving the 115 shaft, rods swingingly supported by the frame and extending between the side portions thereof, a swing seat connecting the rods, means coacting between the shaft and one of the rods for oscillating such rod and consequently the swing seat, and a figure supported upon the swing seat, said figure being of non-opaque material whereby it may be illuminated by light bulbs disposed 120 therewithin.

2. In a sign, a sign frame of hollow construction, a shaft mounted for rotation within the frame, means for driving the shaft, rods swingingly supported by the frame and extending between the side por- 125 130

tions thereof, a swing seat connecting the rods, means coating between the shaft and one of the rods for oscillating such rod and consequently the swing seat, and a non-opaque figure supported upon the swing seat, said figure being costumed and its costume being of non-opaque material, and light bulbs of different colors mounted within the figure in independent circuits where-
5 by the figure may be variously lighted to give its costume different colors.

3. In a sign, a sign body including an open frame, lamps on the frame, rods depending through slots in the top of the

frame and pivotally supported at their upper ends within the top of the frame, a swing seat carried by the rods, a non-opaque figure supported upon the seat, differently colored lamps within the figure, means for energizing the lamps in the figure, means for energizing the lamps on the frame, and means acting on one of the rods to oscillate the seat and figure.

In testimony whereof we affix our signatures.

JOHN R. STARK. [L.S.]
MEADE S. HARWELL. [L.S.]
